UNITED STATES PATENT OFFICE.

WILLIAM KING SMITH, OF WERRIS CREEK, NEW SOUTH WALES,
AUSTRALIA.

DEVICE FOR OPERATING CAR-BRAKES.

SPECIFICATION forming part of Letters Patent No. 782,075, dated February 7, 1905.

Application filed July 7, 1904. Serial No. 215,629.

To all whom it may concern:

Be it known that I, WILLIAM KING SMITH, a subject of the King of Great Britain, residing at Werris Creek, in the State of New South Wales, in the Commonwealth of Australia, have invented certain new and useful Improvements in Devices for Operating Car-Brakes, of which the following is a specification.

My invention relates to an appliance by means of which the air-brakes of a railway-train can be independently applied by a signalman or other person.

It frequently occurs that locomotive-engine drivers are, on account of fogs or for other reasons, unable to see the signals and that trains are wrecked in consequence. Also in the case of washaways, wrecked bridges, landslips, or other sudden and unexpected interruption of the permanent way drivers, especially at night and in inclement weather, occasionally fail to notice temporary danger-signals in time to save their trains. To provide for contingencies such as these, I have devised a mechanism by means of which the air-brakes of a train can be applied by a person stationed elsewhere than on the train.

The essential feature of my invention is an adjustable block which can be secured to the insides of the rails or to a sleeper, so arranged that it can be made to come into operative contact with a tap especially provided on an extension of the pipe of the engine air-brake.

To make my invention clear, I shall now refer to the accompanying sheet of drawings, in which—

Figure 1 is a front view of an engine with my brake-operating mechanism in position, and Fig. 2 is a plan view showing the operating-blocks in position between a pair of rails. Referring to the drawings by the designating characters marked thereon, A A are the rails.

B B are a pair of bed-plates fixed to a sleeper or to the inner sides of the rails.

C C are blocks adapted to slide in suitable guides on the upper faces of the bed-plates B B. As a means for operating said blocks I preferably herein employ a lever D, fulcrumed at d, intermediate the rails A A, the end of the

shorter arm of said lever being movably connected to one of the blocks by means of a link D', a similar link D'' connecting the other block with the longer arm of the lever at a point between the fulcrum and end of said arm. The said end of the longer arm of the lever is connected to an operating hand-lever D'', located beyond one of the rails by means of a rod D', and it is apparent that by properly manipulating the said hand-lever the said blocks C C will be caused to move back and forth in their guides.

E is extension of pipe of train air-brake, carried down sufficiently far to cause the bar-handle F of the tap G to come into contact with the block C when the latter is in the operating position, as shown.

The method of operating my invention is as follows: Where my mechanism is used as an extra safeguard against a train passing an ordinary danger-signal, its operating mechanism would be connected with the signalman's lever-handle in such a way that when he raised the danger-signal he would by the same movement put the sliding blocks C C into the operating position. It is clear that a train can-

not pass the mechanism when the parts are in the operative position, as shown, without the tap-handle F being turned backward and the tap thereby opened. To admit of the application of my invention to a single line on which trains have to run both ways and on which engines must sometimes run tender first, it will be necessary that the tap be made capable of turning only one way and that the downward extension of the air-pipe be hinged so as to permit of a downtrain running over an uptrain obstruction, and vice versa. When it is required to throw my mechanism out of operation, it is only necessary to pull the blocks C C inward into the positions shown in the dotted lines, Fig. 1, in which position the tap-handle F will clear the block C.

A very simple application of my invention is a single block with suitable adjusting clamps or bolts, which a fettler could in a few minutes place in position to prevent a train approaching a washaway or other obstruction on the track.

While I have herein shown a certain preferred embodiment of devices for the purpose named, it will be understood, of course, that I am not limited thereto in precise detail, since 5 immaterial changes therein may be resorted to coming within the scope of my invention.

It is apparent that by disconnecting either one of the links from its block the other block may be operated singly or independently.

10 Having now particularly described and ascertained the nature of my said invention and in what manner the same is to be performed, I declare that what I claim is—

15 In devices of the character referred to, bed- plates disposed alongside the rails of a rail-

way-track, blocks slidably supported by said bed-plates, and means for moving the blocks to operative position, comprising a lever fulcrumed between the track-rails, links connecting the longer and shorter arms of said lever 20 with the blocks, an operating hand-lever located beyond one of the rails, and a connecting-rod between the two levers.

Signed at Sydney, New South Wales, this 20th day of May, A. D. 1904.

WILLIAM KING SMITH.
